(57) **CLAIM**

(21) Appl. No.: **29/177,350**

The ornamental design of an elongated therapeutic treatment device, as shown and described.

(22) Filed: **Mar. 7, 2003**

DESCRIPTION

(51) **LOC (8) Cl.** **24-04**

FIG. 1 is a perspective view of an elongated therapeutic treatment device showing our new design, the elongated therapeutic device is shown broken in the center for ease of illustration;

(52) **U.S. Cl.** **D24/200**

FIG. 2 is a front face view thereof;

(58) **Field of Classification Search** D24/211,

FIG. 3 is a rear face view thereof;

D24/200, 212, 213, 215, 214; 601/134, 135,

FIG. 4 is a side elevational view thereof;

601/136, 137, 128, 201, 108, 204, 109; 600/1,

FIG. 5 is a side elevational view opposite that shown in FIG.

600/9, 12, 13, 14, 16, 18, 15; 128/845

4.

See application file for complete search history.

FIG. 6 is a top view thereof; and,

(56) **References Cited**

FIG. 7 is a bottom view thereof.

U.S. PATENT DOCUMENTS

The broken line disclosure is for illustrative purposes only and forms no part of the claimed design.
